(57) CLAIM

The ornamental design for a pistol, as shown and described.

DESCRIPTION

FIG. 1 is a right front perspective view of a pistol according to the new design;

FIG. 2 is a left front perspective view thereof;

FIG. 3 is a right rear perspective view thereof;

FIG. 4 is a left rear perspective view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a top plan view thereof; and,

FIG. 10 is a bottom plan view thereof.

All broken lines shown in the drawings are for illustrative purposes only and form no part of the claimed design.
